(57) **CLAIM**

The ornamental design for a beverage container, as shown and described.

DESCRIPTION

FIG. 1 is a top perspective view embodying the inventive beverage container;

FIG. 2 is a front side view of the device as seen in FIG. 1, wherein the rear side, left side, and right side are mirror images;

FIG. 3 is a top view of the device as seen in FIG. 1; and, FIG. 4 is a bottom view of the device as seen in FIG. 1. The broken lines within the top surface in FIGS. 1 & 3 in the drawings showing the beverage container illustrate the portions of the beverage container that form no part of the claim. All other broken lines are directed to environmental subject matter and form no part of the claimed design.
